UNITED STATES PATENT OFFICE.

JOHN B. GROMMES, OF CHICAGO, ILLINOIS.

DESIGN FOR A BOTTLE.

SPECIFICATION forming part of Design No. 21,826, dated August 30, 1892.

Application filed April 12, 1892. Serial No. 428,900. Term of patent 14 years.

To all whom it may concern:

Be it known that I, JOHN B. GROMMES, of Chicago, Cook county, Illinois, have invented and produced a new and original Design for 5 Bottles or Flasks, of which the following is a specification.

In the accompanying drawings, Figure 1 is a front elevation of a bottle, illustrating my design; and Fig. 2, a side elevation thereof.

As shown, the body of the bottle A converges at the top to form the neck and the lower corners are rounded off to make the supporting-surface of the bottle somewhat smaller than its body. A shoulder B extends 15 around the upper end of the bottle below the neck, and a similar shoulder C is arranged near the bottom of the bottle. These shoul-

ders give to the bottle the appearance of an extra thickness or covering of glass around the body. 20

In connection with the other features of my design the narrow sides of the bottle have a raised panel D with rounded ends.

The leading features of my design are shoulders on a bottle, extending around its body, 25 and panels arranged on the sides of such bottle.

I claim—

The design for a bottle, as herein shown and described.

JOHN B. GROMMES.

Witnesses:

F. DICHE,

SAMUEL E. HIBBEN.
